Fig. 13.

Fig. 14.

FIG. 1 is a top perspective view of a grinding wheel showing my new design;

FIG. 2 is a top plan view thereof;

FIG. 3 is a side elevational view thereof, looking toward one of the straight side edges thereof;

FIG. 4 is an end elevational view thereof, looking toward one of the curved side edges thereof;

FIG. 5 is a bottom plan view thereof;

FIG. 6 is a top perspective view of a modified form thereof;

FIG. 7 is a top plan view thereof;

FIG. 8 is a side elevational view thereof, looking toward one of the curved side edges thereof;

FIG. 9 is an end elevational view thereof, looking toward the junction of one of the straight side edges with one of the curved side edges thereof;

FIG. 10 is a bottom plan view thereof;

FIG. 11 is a top perspective view of a further modified form thereof;

FIG. 12 is a top plan view thereof;

FIG. 13 is a side elevational view thereof, looking to-

ward the junction of one of the straight side edges with one of the curved side edges thereof;

FIG. 14 is an end elevational view thereof, looking toward one of the curved side edges thereof; and

FIG. 15 is a bottom plan view thereof.

The characteristic feature of my design resides in the alternating arcuate and planar surfaces as shown.

This application is a continuation-in-part of my co-pending applications Serial Nos. D. 67,645 and D. 67,646, both filed November 22, 1961, and now abandoned.

I claim:

The ornamental design for a grinding wheel, substantially as shown and described.
